UNITED STATES PATENT OFFICE.

STERLING ELLIOTT, OF NEWTON, MASSACHUSETTS.

DRINKING-CUP.

1,073,481.

Specification of Letters Patent. Patented Sept. 16, 1913.

Application filed October 24, 1910. Serial No. 588,644.

To all whom it may concern:

Be it known that I, STERLING ELLIOTT, residing at Newton, in the county of Middlesex and State of Massachusetts, have invented 5 an Improvement in Drinking-Cups, of which the following is a specification.

This invention has reference to paper drinking-cups designed to be used once and then destroyed.

10 The cup embodying this invention generally speaking is composed of a single sheet of paper comprising a body-portion having a plurality of slits at its lower edge to form tabs, said body-portion being bent 15 into cylindrical form to produce the body of the cup, and said tabs being turned in and overlapped to form the bottom closure. The tabs are bent inward or folded on a chord of the arc of the body, so that the 20 top of the cup is circular and the bottom is angular, preferably square. In order that the bottom of the cup shall be tight when coated with paraffin-wax it is necessary that it shall be substantially tight before 25 the wax is applied, and considerable difficulty is encountered in constructing and arranging the tabs along the lower edge of the body-portion of the sheet whereby this result may be obtained. The main 30 trouble occurs at the lower end of the side seam of the body-portion, for if a space between the tabs is formed at this point by reason of irregularly or unevenly overlapping the side edges of the sheet when forming the side seam, such space cannot be 35 subsequently filled with wax. I have discovered that by so slitting the end of the sheet that a tab is produced at the lower end of the side seam this trouble is obviated. This tab may be formed by providing narrow tabs at each end of the body-portion, the outer side edges of which are 40 in continuation of the side edges of the body-portion, then when the side edges of the body-portion are overlapped and adhesively secured the outer side edges of these end tabs may be overlapped and adhesively secured and the side seam thus continued uninterruptedly across the middle 45 of the bottom of the cup. While slight variations in securing the side edges of the body-portion will result in corresponding variations in the width of the tab thus formed, no space will be produced.

50 Therefore, my invention has for its object the construction of a cup from a single

piece of paper comprising a body-portion and a plurality of tabs along its lower edge, the end tabs of which are made narrow and the outer side edges of which are in continuation of the side edges of the body-portion of the blank, so that when the body-portion is bent to form the body of the cup and its side edges are overlapped and adhesively secured together the outer side 60 edges of said end tabs will be overlapped and adhesively secured, thereby to form a tab at the lower end of the side seam of the cup, said seam thus continuing uninterruptedly across the bottom of the cup. 65

Figure 1 is a side elevation of a cup embodying this invention. Fig. 2 is a plan view of the cup. Fig. 3 is an underside view of the cup. Fig. 4 is an enlarged vertical section of the bottom of the cup. Fig. 70 5 is a view of the blank of which the cup 75 may be composed.

The blank of which the cup is composed is cut from a sheet or strip of paper, and has a body portion a of large area designed 80 to form the hollow cylindrical body, and has tabs a' , a'' , a''' , a'''' , a''''' , at its lower edge, the end tabs a' and a'''' being made narrow as compared with the other tabs and having their outer side edges in continuation of 85 the side edges of the body portion.

The tabs are here shown as formed by slitting the lower edge of the portion a , and when so formed they are contiguously disposed. This manner of forming the tabs 90 is preferred, but my invention is not limited to so forming them.

The blank is placed on a suitable form and its opposite side edges overlapped and secured together by glue, or other adhesive 95 substance. When securing said edges together the outer side edges of the end tabs a' and a'''' are also overlapped and adhesively secured together, to form a single tab. The single tab thus produced is located at the 100 end of the side seam of the cup body, said seam extending uninterruptedly to the end of the tab. Any variations occurring in forming the side seam will result in correspondingly varying the width of the tab 105 thus produced, but such variations are immaterial as compared with variations in a space which otherwise would be produced at such point. The cylindrical body thus formed may be tapered from end to end to 110 form a conical cup, or it may be made with parallel sides. Each tab is then folded in-

ward on a chord of the arc of the cylindrical body, and, as here shown, four tabs being provided, four lines of fold will be formed, at right angles to each other, hence 5 the bottom of the cup is square. A greater or less number of tabs will result in the formation of an angular bottom of a correspondingly different shape. Said inwardly extended or folded tabs overlie one another 10 and form a bottom closure composed of several superposed layers, and the superposed tabs are secured together by an adhesive substance.

As here shown, one of the tabs as a^3 is 15 made coextensive with the area of the bottom and serves as a main closing tab and as the bottom is here shown as square, said tab has parallel sides; and the two part tab a' , a^3 , is folded inward upon said tab a^3 , and being made of two parts, overlapped and adhesively secured together longitudinally and thereby stiffened, serves as a 20 stiffener for the bottom. The end tabs a' and a^5 which form said single tab have 25 parallel sides as shown in Fig. 5, so that when overlapped and secured together the single tab thus formed has parallel sides, and, like the tab a^3 is made to extend over substantially the entire bottom opening. 30 The intermediate tabs a^2 and a^4 extend over each other and over the aforesaid tabs and hold them, especially until finally set by a suitable adhesive substance.

The shapes of the tabs may be varied 35 more or less as long as they entirely cover the bottom when folded in and secured together.

The cup thus made is then coated with 40 paraffin-wax, as for instance, it may be dipped in melted paraffin-wax, or the melted wax may be sprayed thereon. When thus

coated interiorly or exteriorly, either or both, the cup is waterproof and the bottom sealed. Or waxed or wax-coated paper may be employed in forming the cup, and in such case 45 it will not need to be finally coated with wax, although a final coating is desirable, at least around the bottom, to close and seal any opening which may be formed therein, in the manufacture of the cup. 50

I claim:—

The drinking-cup herein described having a circular top and a square bottom, its bottom-closure consisting of three one-piece tabs and one two-piece tab, said cup, together with the tabs forming its bottom-closure being composed of a single sheet of paper comprising a body-portion having a plurality of slits at its lower edge to form a row of tabs which tabs are adapted to be 60 turned in and overlapped to form the bottom closure, each intermediate tab of the row being made as wide as and forming one side of the bottom of the cup and each end tab being made narrower than the intermediate tabs and having its outer side edge in continuation of the side edge of the body-portion, said narrow tabs overlapping one another and being adhesively 65 secured together when the side edges of the sheet are overlapped and adhesively secured, thus forming a single two-piece tab at the lower end of the side seam which is as wide as and forms one side of the bottom of the cup. 70

In testimony whereof, I have signed my name to this specification, in the presence of two subscribing witnesses.

STERLING ELLIOTT.
